UNITED STATES PATENT OFFICE

PATTERSON O. STEWART, OF NEW YORK, N. Y.

ANTIFOULING SPARK PLUG

Application filed December 6, 1926. Serial No. 152,925.

The present invention relates to spark plugs for internal combustion engines and more particularly to the structure and insulation of spark plug electrodes, whereby fouling of the spark plug by carbon is minimized.

An important feature of the invention is the provision of an annular insulating surface of relatively narrow width separating a grounded and an ungrounded electrode, both appurtenant to the insulator, one of which has a beveled edge that approaches the coacting electrode as it recedes from the face of the insulator.

Another feature of the invention is the provision of a series of subsidiary potential regulator gaps within the insulating body of the spark plug.

Other and further features will be apparent to one skilled in the art after a study of this specification taken in connection with the attached drawings, wherein

Fig. 1 is a longitudinal central sectional view of the device;

Fig. 2 is a sectional bottom plan view of the device on the 2—2 of Fig. 1, looking in the direction of the arrows of said line.

Referring to Fig. 1, the body or core 10 of the spark plug, which is of suitable insulating material, is provided at its upper portion with the central chamber 11 having at its bottom the bore 12 extending through the lower portion of the body and terminating at the lower end of the end portion 13a of reduced diameter below the tapered portion 13 of the body.

The body or core 10 is received in the shell 14 of the spark plug being held therein by the threaded metal gland 15, the body 10 having the enlarged portion 16, a packing ring 17 being disposed between the upper end of the portion 16 and the lower end of the gland 15 and a packing ring 18 being disposed between the lower end of a shell 18a encasing said portion 13a and the ledge 19 at the lower end of the shell 14 for preventing loss of compression. The tapered end 13 of the body 10 is located in the chamber 20 formed by the lower portion of the shell 14.

The relatively thick disks 21 of conductive material are arranged in overlying and

underlying relation in the chamber 11, the lowermost 22 of these disks resting on the bottom of the chamber and having therein the threaded aperture 23, the disks 21, 22 being separated by the annular spacing members 24 of insulating material for thereby providing spark gaps between the disks.

The domed metal cap 25 has secured thereto or formed as part thereof, the outwardly extending terminal stem 26 for connection to a supply of electricity, not shown, the stem 26 having the head 27 located under the domed portion of the cap. The cap 25 is secured over the upper end of the body 10, the concaved-convexed plate member 28 being loosely located in the space between the under side of the dome of the cap 25 and the uppermost of said disks 21 at the upper end of the body 10, the concave side of this plate member 28 bearing against the head 27 of the stem 26 and the convexed side of the plate member bearing on the uppermost of the disks 21 and thereby retaining the disks 21, 22 in the chamber 11.

The metal stem 29 is received in the bore 12, threadedly engaging at one of its ends in the aperture 23 of the disk 22 and having at its other end the sparking member or head 30, the stem 29 and head 30 constituting the ungrounded electrode of the spark plug. A downwardly extending and inwardly tapering ring 31 at the inner edge of a flange 32 at the lower end of said shell 18a constituting the grounded electrode of the spark plug.

By referring to Fig. 1, it will be noted that the circular head 30 of the stem 29 has its bottom edge in substantially the same horizontal plane as the annular end portion 31 of the shell 18a, a gap being formed between the head 30 and the annular end 31 of the shell 18a and of least width between the bottom edge of the head 30 and the bottom edge of the annular end portion 31, the intention being that sparks passing across said gap from the head 30 to the ring 31 shall pass from various parts of the circumferential edge of the head 30 and not be confined to any particular part of the head 30.

The lower portion 13a of the body of the insulator extends into the interior of the shell

14 of the spark plug. This form is intended for use in engines having relatively high compression ratios.

The operation of this invention in use in a motor properly adjusted and not "pumping oil" is practically the same as any spark plug of conventional design, but for illustration, say, the motor starts to "pump oil" and the carburetor supplies a mixture 10 slightly over-rich in fuel content, then at once the walls of the combustion chamber, including the portions of the spark plug exposed to the explosion flame are subjected to carbonizing, the partially burnt excess 15 lubricating oil acting as a binder and forming with the unconsumed portion of hydrocarbon in the mixture an amorphous carbon. The carbon is thus forming on the insulator of a spark plug of conventional design, acts 20 as a high resistance leak between the electrodes and as the carbon coating gets thicker from continued operation, the resistance is lowered until the plug ceases to fire, whereas with a spark plug designed as herein described the action is entirely different, as 25 will be described.

Referring to Fig. 1 of the annexed drawings it will be observed that the insulating space 31a between the grounded electrode 30 31 and the head 30 of the ungrounded electrode is very narrow, being in fact only a few thousandths of an inch wider than the spark gap, as the carbon forms on this narrow insulating space sufficiently to lower its 35 resistance to or below that of the spark gap the current will flow across at that point but this high resistance short being so narrow the current will heat the carbon to incandescence and it will therefore be dissipated or consumed, any leakage of current 40 that might take place across the above mentioned high resistance short circuit is precluded by the series gaps 24 which hold the current in check until the voltage builds up 45 to a high enough potential to produce a comparatively high ampere-flow. As can be seen, this structure also allows the insulating space 31a to be kept at a comparatively high temperature by the explosion flame tending 50 to vaporize or dry any oil that might be deposited thereon.

The invention is presented as including also such modifications and changes as may 55 property come within the following claims.

What I claim and desire to protect by Letters Patent is:

1. In combination, a body of insulating material having an axial bore therethrough enlarged at its upper portion to form a chamber; a frequency changer comprising spaced metallic disks disposed in said chamber, a terminal stem connected to the topmost disk; an electrode stem in said bore connected to the lower disk and provided at its outer end 60 with a disk shaped sparking electrode head 65

formed with an annular sparking part spaced from said insulator; and an electrode co-operating with said part to form a spark gap.

2. In combination, a cylindrical metallic shell; a body of insulating material therein 70 having a downwardly tapered lower end and an axial bore therethrough enlarged at its upper portion to form a cylindrical chamber; a series of spaced thick metallic disks and insulating spacing ring members alternated 75 therewith superposed in said chamber, the lowest disk resting on the bottom of said chamber and provided with a central threaded aperture; a terminal stem connected to the topmost disk; a metal electrode stem in said bore of the body and having a reduced inner threaded end engaged in said aperture of the disk and provided at its outer end with a 80 sparking part; and an electrode adjacent to said part and grounded on said shell. 85

3. In combination, a body of insulating material having an axial bore therethrough enlarged at its upper portion to form a chamber; a frequency changer comprising spaced metallic disks disposed in said chamber; said 90 body having an annular groove around the upper end; a dome-topped metal cap secured on the upper end of said body and provided with an upper central opening and a lower inwardly pressed rib engaged in said groove; a 95 downwardly concavo-convex plate member in said cap and pressed against the topmost disk; a threaded terminal stem in said opening and having a head disposed between said plate member and dome top; an electrode stem 100 in said bore connected to the lower disk and provided at its outer end with a sparking part; and an electrode co-operating with said part to form a spark gap.

Signed at New York in the county of New 105 York and State of New York this 4th day of December, A. D. 1926.
